DESIGN FOR A TONGUE BRUSH

George L. Grapp, Seattle, Wash.

Application February 25, 1936, Serial No. 61,345

Term of patent 14 years

To all whom it may concern:

Be it known that I, George L. Grapp, a citizen of the United States, residing at Seattle, in the county of King and State of Washington, have invented a new, original, and ornamental Design for Tongue Brushes, of which the following is a specification, reference being had to the accompanying drawing, forming part thereof.

I claim:

The ornamental design for a tongue brush, as shown.

Signed at Seattle, this 19 day of February, 1936.

GEORGE L. GRAPP.
